UNITED STATES PATENT OFFICE

CHARLES A. DICKENS, OF HAGERSTOWN, MARYLAND, ASSIGNOR TO DICKENS AUTO TRANSMISSION HOIST COMPANY INC., OF HAGERSTOWN, MARYLAND

HOIST

Application filed September 16, 1931. Serial No. 563,212.

This invention relates to a hoist and has for its primary object to provide, in a manner as hereinafter set forth, a device of this character which is portable and which embodies a novel construction, and arrangement of parts, whereby same is adapted particularly for use in removing and replacing transmission units of automobiles in an expeditious manner.

10 Other objects of the invention are to provide a transmission hoist which will be simple in construction, strong, durable, efficient and reliable in use and which may be manufactured at low cost.

15 All of the foregoing and still further objects and advantages of the invention will become apparent from a study of the following specification, taken in connection with the accompanying drawings, wherein like characters of reference designate corresponding parts throughout the several views, and wherein:—

Figure 1 is a view in vertical section through a hoist constructed in accordance 25 with the present invention.

Fig. 2 is a view in vertical cross section taken substantially on the line 2—2 of Fig. 1, looking in the direction indicated by the arrows.

30 Fig. 3 is a view in horizontal cross section taken substantially on the line 3—3 of Fig. 1, looking downwardly as indicated by the arrows.

Fig. 4 is a view in top plan showing the 35 hoist in position for use.

Fig. 5 is a vertical sectional view taken substantially on the line 5—5 of Fig. 1.

Fig. 6 is a vertical sectional view taken substantially on the line 6—6 of Fig. 1.

40 Fig. 7 is a detail view in perspective of one of the transmission supporting bars.

Referring now to the drawings in detail, it will be seen that the hoist constituting the present invention comprises a tubular bar 1 which extends slidably thru the horizontally disposed feet 2 and which has its ends provided with the caps 3. These feet 2 are equipped with the supporting casters 4. The reference numeral 5 designates rods which are 50 disposed in spaced parallelism with the tubu-

lar barrel 1 on opposite sides thereof, and upon which the feet 2 are also slidable. On their ends, the rods 5 are provided with the caps 6.

The feet 2 are provided with the upstanding socket members 7, for removably receiving the lower end portions of the vertically extensible standards which are designated generally by the reference numeral 8. The standards 8 include the tubular lower members 9 which are engageable in the sockets 7. The standards 8 further include the upper members 10 which telescope into the lower members 9.

55 The members 9 and 10 are provided with a series of openings 11 which are adapted to be brought into registry for the reception of the pins 12 for securing the upper members 10 in adjusted position. The pins 12 may be secured to the lower members 9 of the standards 8, through the medium of a chain 13, and a ring 14.

60 One of the upper members 10 of the standards 8, is provided at its upper end, with a bearing 15 in which one end portion of a 70 horizontally disposed tubular shaft 16 is journaled. The other upper member 10 has rigidly mounted thereon an upstanding casing 17 which is secured in position in any suitable manner, as by a pin 18. A shaft 19 is journaled horizontally in the casing 17 and has an enlarged end portion 20 projecting therefrom for engagement in the other end portion of the tubular shaft 16 for supporting same.

65 Suitable means, such as a pin 21, is employed for connecting the tubular shaft 16 to the enlarged projecting end portion 20 of the shaft 19 for rotation with said shaft 19. The inner end of the enlarged portion 20 of the shaft 19 is provided with a collar 22 against which the adjacent end of the tubular shaft 16 abuts.

75 A worm gear 23 is fixed on the shaft 19 in the casing 17. Journalled in the casing 17 above the shaft 19 and at right angles thereto, and projecting from the said casing 17 is a shaft 24 having fixed thereon a worm gear 25. A hand crank 26 is mounted on the projecting end portion of the shaft 24 for 100

manually rotating said shaft. If desired, the hand crank 26 may be removable. A hoisting chain 27 has one end fixed to the tubular shaft 16 and is windable thereon.

If desirable or necessary, more than one hoisting chain 27 may be provided. The end of the tubular shaft 16 which is supported in the bearing 15 is provided with a cap 28.

Mounted for sliding adjustment on the rods 5 are the anti-clinal transmission supporting bars 29, the apex portions of which rest on the tubular bar 1. At their ends the bars 29 terminate in the upstanding eyes 30 which slidably encircle the rods 5. The bars 29 are slidably adjustable toward and away from each other to accommodate different sides of transmission units. In Fig. 4 of the drawings, a transmission unit is designated by the reference numeral 31, the same being shown in broken lines. A portion of the frame of a vehicle is also shown in broken lines in Fig. 4 of the drawings and designated by the reference numeral 32.

In use, the floor boards of the vehicle which are forward of the driver's seat are removed. The feet 2, with the standards 8 and tubular shaft 16 removed therefrom are then rolled under the vehicle into position beneath the transmission. The standards 8 are then mounted in the socket members 7 and the members 10 of said standards are adjusted vertically as desired. Then, the tubular shaft 16 is mounted in position and extends transversely above the transmission. The hoisting chain 27 is then secured properly to the transmission after which said transmission may be unbolted and lowered to the supporting bars 29. The worm gears 23 and 25 prevent rotation of the tubular shaft 16 except when actuated by the hand crank 26. With the transmission resting on the bars 29, the tubular shaft 16 and standards 8 are again removed in order that the lower portions of the hoist with the transmission thereon may be rolled from beneath the vehicle.

It is believed that the method of replacing the transmission will be apparent from the foregoing description.

It is believed that the many advantages of a hoist constructed in accordance with the present invention will be readily understood, and although the preferred embodiment of the invention is as illustrated and described, it is to be understood that changes in the details of construction and in the combination and arrangement of parts, may be made which will fall within the scope of the invention as claimed.

Having thus described my invention, what I claim as new is:—

1. A hoist comprising a bar, a pair of feet slidable on the bar for adjustment toward and away from each other, supporting casters on the feet, standards rising from the feet, a shaft rotatably mounted on the standards,

means windable on the shaft for suspending a load thereon, and means for manually rotating the shaft.

2. A hoist comprising a bar, a pair of feet 70 slidable on the bar for adjustment toward or away from each other, standards on the feet, a horizontally disposed shaft, means on one of the standards, for rotatably supporting one end of the shaft, means on the other standard for rotatably supporting the other 75 end of the shaft, means on said other standard for manually actuating the shaft, and means windable on the shaft for suspending a load thereon.

3. A hoist comprising a bar, a pair of feet 80 slidably adjustable on the bar for movement toward and away from each other, supporting casters on the feet, socket members rising from the feet, vertically extensible standards 85 removably mounted in the socket members, standards each comprising a tubular lower member engageable in the socket members, and an upper member slidable in said lower member, means for releasably securing the upper members in adjusted position on the lower members, a bearing on the upper end of one of the upper members, a casing mounted on the upper end of the other upper member, a shaft rotatably mounted in the casing and including an enlarged end portion projecting from said casing, means for manually rotating the shaft, a tubular shaft having one end portion journaled in the bearing and its other end portion engaged over the projecting end portions of the first-named 90 shaft and secured thereto for support and actuation hereby, and means windable on the second-named shaft for suspending a load thereon.

4. A hoist comprising a bar, a pair of rods 105 disposed on opposite sides of the bar in spaced parallelism therewith, a pair of feet slidable on the bar and on the rods for adjustment toward or away from each other, standards rising from the feet, a shaft rotatably mounted on the standards, means for actuating the shaft, means windable on the shaft for suspending a load thereon, and a pair of bars extending between the rods and 110 slidably connected thereto for adjustment toward or away from each other and adapted to receive and support the load.

5. A hoist comprising a bar, a pair of rods disposed on opposite sides of the bar in spaced parallelism therewith, a pair of feet 115 slidable on the bar and on the rods for adjustment toward or away from each other, standards rising from the feet, a shaft rotatably mounted on the standards, means for actuating the shaft, means windable on the shaft for suspending a load thereon, a pair of bars extending between the rods and 120 slidably connected thereto for adjustment toward or away from each other and adapted to receive and support the load, the last-named bars having 125

their intermediate portions engaged for rest on the first-named bar, and eyes on the ends of said last-named bars slidably encircling the rods.

- 5 6. A hoist comprising a pair of spaced parallel rods, a bar disposed between the rods in spaced parallelism therewith, a pair of feet slideable on the bar and on the rods for adjustment toward or away from each other,
- 10 10 a pair of substantially anti-clinal bars extending over the first-named bar between the rods, the intermediate portions of the second-named bars being engaged for rest on the first-named bar, eyes on the ends of the second-named bars slidably encircling the rods for mounting the second-named bars thereon for adjustment toward or away from each other, said second-named bars being adapted to receive and support a load, and
- 15 20 means for lowering a load onto the second named bars or raising said load therefrom.
- 25 7. A hoist comprising a pair of spaced parallel rods, a bar disposed between the rods in spaced parallelism therewith, a pair of feet slideable on the bar and on the rods for adjustment toward or away from each other, a pair of substantially anti-clinal bars extending over the first-named bar between the rods, the intermediate portions of the second-named bars being engaged for rest on the first-named bar, eyes on the ends of the second-named bars slidably encircling the rods for mounting the second-named bars thereon for adjustment toward or away from each other, said second-named bars being adapted to receive and support a load, means for lowering a load onto the second-named bars or raising said load therefrom, said means including socket members, rising from the feet, vertically extensible standards removably mounted in the socket members, a horizontally disposed shaft removably and rotatably mounted on the standards, a crank operatively connected to the shaft for manually rotating same, and a chain windable on the shaft for engagement with the load for suspending said load from the shaft.

In testimony whereof I affix my signature.

CHARLES A. DICKENS.
